HOSE NOZZLE

Vincent Bernesser, Shandaken, N. Y.

Application February 6, 1936, Serial No. 62,563

1 Claim. (Cl. 240—2)

My invention relates to hose nozzles for use with gasoline or oil.

The object of my invention is to provide a hose nozzle of the type used in filling the tanks of 5 automobiles with gasoline supplied by pumps at a supply station, with means for illuminating the interior of such a tank while it is being filled with gasoline, and also to provide a nozzle which comprises a flash-light which may be used to illuminate the dials of the pumps from which the gasoline is obtained.

A further object is to provide a nozzle in which the illuminating means is located within the cylindrical conduit or wall of the nozzle adjacent its 15 outlet end so as to afford no obstruction in inserting the nozzle in the tank, and also to protect the illuminating means from injury in handling the nozzle.

A further object is to provide a nozzle and flash-light combination in which the body of the nozzle serves as a handle for the flash-light and to hold it firmly in the upper side of the nozzle outlet.

Referring to the drawing which forms a part 25 of the specification;

Fig. 1 is a longitudinal view of my nozzle and flash-light, shown partly in section.

Fig. 2 is a view of the outlet end of the nozzle.

Fig. 3 is a longitudinal sectional view of the 30 nozzle, shown with the flash-light casing combined therewith as in Figure 1, but using electrical conductors leading to a source of electrical supply, the wires being supported by the hose thru which the gasoline flows in filling the tank.

10 indicates a hose leading to a gasoline pump, and 11 a hose nozzle connected thereto in the usual manner.

The nozzle wall or conduit is bent to form an 40 elbow to provide an outlet end extending at an angle to the shank portion 11' which is connected with the hose 10.

The upper side wall of the portion 12 is formed with a wide slot 13 which extends the entire length thereof and into the straight or shank portion of the conduit wall, and the flash-light casing 14 is fitted therein so that its upper side will be 5 practically flush with the outer surface of the conduit, as illustrated in Figure 2, and is made integral therewith by mechanical means.

In Figures 1 and 3, 15 indicates the lamp, and 16 the lens therefor, and 17 indicates the manually operated switch handle.

In Figure 1, the lamp is shown connected with dry batteries 18 in the usual manner, while in Figure 3, the lamp is supplied by a battery 19 thru conductors 20, the conductors being supported by the hose to which they are secured by ring clamps 21 placed at suitable distances apart as will be readily understood.

The flash-light casing extends beyond the wall of the nozzle as shown at 14', thus making it 20 convenient to replace exhausted batteries therein, and this extension also serves as a guide for the hand in holding the nozzle and in operating the switch 17.

The use of the lamp with the nozzle permits 25 observation of the gasoline as it fills the tank so that it will not be permitted to overflow by the attendant.

Having thus described my invention I claim as new:

A hose nozzle of the character described comprising a cylindrical conduit of sheet metal formed with an elbow at a predetermined distance from its outlet end, originally having a longitudinally extending slot formed in the upper wall of the 35 conduit which extends beyond the end of the elbow; a flash-light comprising a separate casing which is sealed in and closes said slot and is joined to the conduit in fluid tight relation and extends beyond said elbow and the body portion 40 of which rests in said conduit.

VINCENT BERNESSER.
